UNITED STATES PATENT OFFICE

2,628,014

MULTIPLE STAGE NONSLIP VACUUM PUMP

Michael Pemmerl, Chatham, N. J., assignor of
one-half to Max Raskin, Chatham, N. J.

Application August 17, 1950, Serial No. 179,981

9 Claims. (Cl. 230—45)

1

The invention relates to rotary pumps of the type wherein two segmental pistons rotate in the same direction about a common axis in a cylindrical working chamber having intake and outlet ports and are driven alternately at high and low angular speeds in such relation to the chamber ports that, during each cycle of operation, fluid is sucked through the intake port into the space between two separating working faces of the pistons at the same time that fluid previously entrained between the other working faces of the pistons is expelled through the outlet ports as these latter faces close upon each other.

Prior to the present invention, rotary pumps of this type have involved a single stage of pumping action, during which retrograde slip of fluid past the frictional faces of the pistons and chamber walls occurs and is especially aggravated when the fluid being pumped is air or other gases. Consequently, when the single stage principle has been adopted for vacuum pumps, it has not been possible to produce a vacuum of sufficiently high degree for certain industrial purposes, such as in the evacuation of radio and television tubes.

It, therefore, is the principal object of the present invention to provide an improved vacuum pump wherein slip is neutralized by adding at least one additional stage of pumping action following the heretofore practiced single, or basic, stage. To be more explicit, the improvement consists in subjecting the fluid which is being expelled from the working chamber of the basic pumping stage to suction created in the working chamber provided for the additional pumping stage before there has been any opportunity for slip to occur. Successful achievement of the slip-neutralization action is evidenced by the increased rate and smoothness of pull on the fluid being evacuated.

In a single stage rotary pump, the two pistons come together at one side of the rotational axis in dead-center condition once in each operational cycle and thus create a state of imbalance which, though only momentary, is quite objectionable. Consequently, in applying an additional pumping stage for slip-neutralization, the pistons in the additional working chamber have been so disposed in coordination with the pistons of the basic pumping stage that the pistons of both chambers will assume their dead-center conditions when located at diametrically opposite sides of the rotational axis in balancing relation to each other. The achievement of this state of balance, however, has the disadvantage of causing inter-chamber slip between certain areas of the frictional surfaces and thus impairs the efficiency of both stages.

2

Due to this situation, it is a further object of the invention to restore the full efficiency of the basic and primary slip-neutralization stages by adding a secondary slip-neutralization stage embodied in a third working chamber and set of pistons therefor.

In applying the third pumping stage, the additional set of pistons have been so arranged and operationally coordinated with the other pistons that they will assume dead-center condition in a position in axial alignment with the pistons of the basic stage, which means that these two sets of pistons will be diametrically opposite to the pistons of the primary slip-neutralization and again will produce a state of imbalance.

Consequently, it is another object to include in the driving mechanism for the pistons special means for restoring the balance thereof to the maximum degree practicable.

20 A still further object of the invention is to provide a specific construction of multiple stage pump which is characterized by extreme simplicity, compactness, economy of materials, and smooth operational efficiency.

25 Other objects and advantages will appear as the following specific description is read in connection with the accompanying drawings, in which:

Fig. 1 is a side elevation of the complete pump, with the concealed piston assembly stopped in mid-cycle condition; Fig. 2 is an end elevation of the same, partly in section; Fig. 3 is a top plan view partly in section; and Fig. 4 is a large scale longitudinal vertical section on line 4—4 of Fig. 2.

30 Fig. 4A is a large scale fragmentary longitudinal vertical section of the casing unit and piston unit alone taken on line 4—4 of Fig. 2, showing the piston unit stopped at the end of an operational cycle.

35 Fig. 5 is a transverse vertical section on line 5—5 of Fig. 4A; and Fig. 5A is a similar view on line 5A—5A of Fig. 4.

40 Fig. 6 is a transverse vertical section on line 6—6 of Fig. 4A, showing the mid-cycle piston positions in broken lines.

45 Fig. 7 is a similar view on line 7—7 of Fig. 4A.

Fig. 8 is a transverse vertical section on line 8—8 of Fig. 4; and Fig. 8A is a similar view showing the linkage arrangement corresponding to the dead-center piston condition represented in Figs. 4A, 5, 6 and 7.

50 Fig. 9 is a diagrammatic view embracing the three pumping stages to demonstrate the slip-neutralization effect of the primary and secondary stages of neutralization.

55 Referring now in detail to the drawings, wherein like reference characters designate

corresponding parts in the several views, the improved pump comprises three major assembly units, viz.: casing unit A, piston unit B and differential drive unit C.

Casing unit A provides three distinct working chambers 10, 11 and 12 of circular cross-section in which the three cooperative stages of pumping action are performed by piston unit B when installed therein and operated by differential drive unit C. In practice, casing unit A may take various structural forms within the scope of the invention, but it is preferred to arrange working chambers 10, 11 and 12 in concentric alignment and to insure as fluid-tight a structure as possible, so a one-piece cylindrical body 13, which may be supported in a horizontal position on base 13', has been adopted to constitute the principal element of said casing unit. For reasons which will become apparent as the description progresses, body 13 has been bored longitudinally to provide working chambers which are stepped up in diameter from one end of said body to the other but are of substantially the same length. Working chamber 10, which is at the intake end of the pump, as will be specified in greater detail later, has the smallest cubical capacity of the series of chambers and working chamber 12, which is at the discharge end, has the greatest capacity. The annular shoulder 14 formed at the juncture of working chamber 10 with working chamber 11 and the similar shoulder 15 at the juncture of working chamber 11 with working chamber 12 serve a special purpose which will be described later in connection with specific description of piston unit B.

The open ends of the casing bore are adapted to be closed by end plates 16 and 17, respectively, with plate 16 forming the outer end wall of working chamber 10 and plate 17 forming the outer end wall of working chamber 12. End plates 16 and 17 preferably are detachably secured to body 13 by screws 16' and 17'. However, it is a useful feature of the invention that end plate 17 shall normally form a part of piston unit B so that said plate is always in correct position to be applied to casing body 13 whenever said piston unit is inserted into the bore thereof. Division walls between working chambers are required, but it is a feature of the present invention that, instead of being provided in casing unit A, the necessary walls for this purpose are incorporated in piston unit B to attain the simplicity of construction which has been advanced as one of the objects of the invention. Therefore, detailed description of the division or partitioning walls will be postponed until the subject of piston unit B has been reached herein.

Body 13 is provided with intake ports 18, 18' and 18'' and with outlet ports 19, 19' and 19'', respectively, for working chambers 10, 11 and 12. Intake port 18 and outlet port 19'' are adapted to be connected to the suction and discharge pipes of the pumping or air evacuating system for which the pump is designed. Referring particularly to Figs. 5 and 7, it will be observed that intake port 18 and outlet port 19 for working chamber 10 and intake port 18'' and outlet port 19'' for working chamber 12 are all disposed in communication with the upper areas of said working chambers, whereas Fig. 6 discloses the fact that intake port 18' and outlet port 19' for working chamber 11 are in communication with the lower area of the latter. The reason for this staggered arrangement will appear as the description progresses.

In accordance with the concept of slip-neutralization advanced herein, outlet port 19 for working chamber 10 is connected by a communicating duct 20 with intake port 18' for working chamber 11. Similarly, outlet port 19' for working chamber 11 is connected by communicating duct 21 with intake port 18'' for working chamber 12. It is within the scope of the invention to employ any suitable means for providing the two communicating ducts 20 and 21 but it is preferred to use externally located tubing 22 and 22' for this purpose.

End plates 16 and 17 of casing unit A, when in applied positions, are located suitably to support journaling means for both ends of piston unit B, which will now be described.

Referring particularly to Fig. 4, it will be observed that piston unit B includes a central driven shaft 23, which has a driven sleeve 24 rotatably enclosing the left end portion thereof. The right end of driven shaft 23 is adapted to be journaled in a bearing boss 25 provided centrally on end plate 16 of casing unit A, whereas driven sleeve 24 is adapted to be journaled in a bearing boss 26 provided centrally on end plate 17. Driven sleeve 24 thus is rotatable in end plate 17 and in turn serves to journal the left end of driven shaft 23. Driven sleeve 24 is integral with the hub of a preferably hollow segmental piston 27 which is disposed in working chamber 12 in cooperation with a structurally mated piston 28, which also is preferably hollow. The hub of piston 27 is rotatable with driven sleeve 24 on driven shaft 23 and extends throughout nearly half the length of working chamber 12, whereas the head of the piston extends from the outer end of said chamber nearly to the other end. The inwardly projecting half of piston 27 overlies and bears against the hub of piston 28, whose projecting half similarly overlies and bears against the hub of piston 27, all in the manner well known in the art. Piston 28 is affixed by suitable removable means, such as cross-pin 29, to driven shaft 23 for rotational movement therewith. The external dimensions of pistons 27 and 28 should be such that they frictionally bear against the end and peripheral surfaces of working chamber 12 in as nearly fluid-tight a manner as may be effected between any moving parts. The inner end wall of working chamber 12 is formed by a centrally perforated partitioning disc 30 which separates the said working chamber from adjoining working chamber 11 and is rotatably mounted on driven shaft 23 in abutting relation to the flush inner (right) end faces of pistons 27 and 28. The thickness of partitioning disc 30 should be substantially equal to the distance remaining between the inner end faces of pistons 27 and 28 and shoulder 15 of the outer chamber wall. The external diameter of partitioning disc 30 should be such that it will frictionally bear against the peripheral surface of working chamber 12.

Working chamber 11 is provided similarly to working chamber 12 with a pair of coating pistons 27' and 28' of proportionately smaller size than pistons 27 and 28 and which preferably are solid in construction. Piston 28' is affixed to driven shaft 23 for rotation therewith, as by cross-pin 29', but it is intended that piston 27' shall rotate with piston 27 of working chamber 12, so partitioning disc 30 is affixed to said pistons 27 and 27' by removable means such as stud bolts 31. It will be observed that piston 27' is set diametrically opposite to piston 27 with respect to the axis of driven shaft 23. The reason for

this arrangement will appear when the operation of the pump is described later herein.

Working chamber 10 is provided with a pair of hollow coating pistons 27" and 28" of proportionately smaller size than pistons 27' and 28' of working chamber 11. In like manner, piston 28" is affixed to driven shaft 23 by removable means, such as cross-pin 29", and piston 27" is joined to piston 27' for movement therewith through the medium of a second partitioning disc 32 and by the use of attaching means such as stud bolts 33. This second partitioning disc 32 is proportioned to rotate in working chamber 11 in substantially air-tight abutting relation to the peripheral surface thereof and to shoulder 14. In this instance, piston 27" is set diametrically opposite to piston 27' and in axial alignment with piston 27.

Referring now to Figs. 5, 6 and 7, it will be observed that each piston subtends an arc of substantially 90 degrees between its leading and trailing axial working faces 34 and 35, respectively; also that the associated intake and outlet ports for each working chamber are disposed in substantially horizontal alignment either above or below the rotational axis of the piston unit and that they open into the working chamber through arcuate grooves 36. Each groove 36 extends through an arc of substantially 90 degrees and both grooves of the pair associated with any one working chamber are separated at their ends most remote from the horizontal plane in which the rotational axis lies by a narrow land 37 which is bisected by the vertical plane through said rotational axis. In the case of working chambers 10 and 12, the intake and outlet ports are in communication with the upper areas thereof, so land 37 is located at the uppermost point. On the contrary, the intake and outlet ports for working chamber 11 communicate with the lower area thereof, so land 37 is at the lowest point. In either case, the land 37 occupies a dead-center position, or starting and stopping point, for each cycle of pumping operation within the working chamber. Due to the specific piston and port relation just described, when both pistons in any working chamber are in the dead-center condition represented in Figs. 5, 6 and 7 in solid lines, adjacent working faces of the pistons will be slightly separated and the space therebetween will be masked by land 37; also the pistons will substantially span the arcuate grooved portions of the respective ports.

By comparing the structural proportions disclosed in Figs. 5, 6 and 7, it will be apparent that the piston displacement is graduated through working chambers 10, 11 and 12. The difference in displacement between working chamber 10 and working chamber 11 is substantially equal to the interior fluid volume of communicating duct 20, so that each operational cycle of the pistons in working chamber 11 will cause the fluid in said duct to be sucked into working chamber 11 first and then the fluid displaced by the pistons of working chamber 10 will be sucked in. In this way, all of the fluid evacuated by the basic pumping stage in working chamber 10 will be accommodated in working chamber 11 without the usual back pressure and slip. In like manner, the displacement difference between working chambers 11 and 12 is substantially equal to the interior fluid volume of communicating duct 21 which leads from the outlet port of the former chamber to the intake port of the latter.

Various types of differential driving mecha-

nisms generally suitable for the operation of piston unit B are well known to the art and available for selection. Because it lends itself to the incorporation of piston balancing means which forms part of the present invention, the linkage type of driving mechanism has been adopted.

Referring now to Figs. 1, 2, 8 and 8A in particular, it will be observed that driving unit C includes a cylindrical drum 38 which has central apertures 39 and 40 in its inner and outer end walls 41 and 42, respectively, in concentric relation to the drum axis. Inner aperture 39 has an exteriorly projecting bearing boss 43, which is adapted to rotatably engage an external peripheral bearing surface 44 provided on bearing boss 24 of end plate 17 in eccentric relation to the axis of driven shaft 23 of piston unit B. The axis of bearing surface 44 is disposed directly beneath the axis of driven shaft 23. When drum 38 of differential driving unit C is thus mounted for rotation on an axis eccentric to the axis of rotation of piston unit B, bearing boss 43 of the former will frictionally abut the adjacent vertical face of end plate 17.

Driving linkage 45 interconnects drum 38 with driven shaft 23 and driven sleeve 24 of piston unit B, and includes a crank 46 whose hub 47 is removably affixed, as by cross-pin 48, to the outer (left) end of driven shaft 23. A cooperative crank 49 has its hub 50 removably affixed, as by key 51, to driven sleeve 24. Hub 50 of crank 49 is confined between hub 47 of crank 46 and bearing boss 26 of end plate 17 and thus is in substantial axial alignment with said hub 47. Roughly, crank 49 may be described as lying in the plane of its hub 50, whereas crank 46 is axially offset inwardly to cause it to overlie hub 50 of crank 49 in the plane of the latter. Each of said cranks 46 and 49 is bifurcated radially outward from its hub. The bifurcated portion of crank 46 straddles the inner end of a preferably bowed link 52 and is pivotally connected to the latter by a removable axially disposed screw pin 53, which is adapted to be operated in application or detachment by insertion of any suitable turning tool (not shown) through aperture 40. The outer end of link 52 is pivotally connected to drum 38 by means of a removable screw pin 54, which is terminally engaged with both end walls 41 and 42 in axial spanning relation thereto. In like manner, a similar link 55 has its inner end pivotally connected to crank 49 by screw pin 56 and its outer end connected to the end walls of drum 38 by screw pin 57. The specific construction of cranks 46 and 49 and the arrangement of said cranks and links 52 and 55 in relation to the dead-center positions of the pistons of piston unit B is such that each leading piston of the pair in each working chamber will be driven through the complete 360 degrees of one operational cycle while the trailing piston is driven 90 degrees, or one-fourth as fast in angular speed. Upon completion of each cycle, the order of fast and slow movement of the pistons of each pair will be reversed, this alternating differential driving motion being in conformity with the well known mode of operation of single stage rotary pumps.

It has been stated previously herein that pistons 27-28 and 27'-28' are hollow in structure whereas pistons 27"-28" are solid. This difference serves to reduce the degree of imbalance of the diametrically opposed sets of pistons to a minimum. Attention is now invited to the fact that cranks 46 and 49 of differential driving unit C are enlarged in size and mass beyond what

would seem to be necessary. The reason for this enlargement is to make the cranks so heavy that, when they are disposed below the rotational axis of piston unit B in the positions shown in Fig. 8A and all of the pistons thereof are in dead-center condition, the weight of said cranks will counter-balance the excess weight of hollow pistons 27-28 and 27'-28' over solid pistons 27-28'. The weight may be increased for a given size of crank by making it of metal that is heavier than that of which the pistons are made. This balancing feature is very important and makes the pump vibrationless and quiet in operation.

The pump is adapted to be driven by any suitable prime mover, such as an individual electric motor (not shown). To this end, a cupped face plate 58 is provided for fixed connection to shaft 59 of the motor and detachable connection to outer end wall 42 of drum 38 by such means as screws 60. It will be noted that drum 38 is well adapted to serve as a pulley for engagement by the drive belt (not shown) of some other type of power system.

Due to the unit assembly feature, assembling the three principal units and dismounting the same is greatly simplified. For instance, assuming that the pump is completely assembled as illustrated in Figs. 1 to 4, inclusive, it may be separated into its component units in the following manner. First, face plate 58 is detached from its connection with drum 38 of differential drive unit C and said face plate and the motor are moved out of the way. Then, differential driving unit C is disconnected from piston unit B by simply knocking out cross-pin 48 and then pulling drum 38 axially outward until it is clear of the end of driven shaft 23. After differential driving unit C has been moved out of the way, screws 17' may be unscrewed to free end plate 17 from body 13 of casing unit A, whereupon the entire piston unit B, together with the integral partitioning means for working chambers 10, 11 and 12 constituted by partitioning discs 30 and 32, may be extracted bodily from the left end of the casing bore. The advantages of this unit assembly feature should be self-evident.

The operation of the pump is likewise extremely simple though productive of results heretofore unknown. Referring now to diagrammatic Fig. 9, it will be seen that, as the pistons in working chamber 10 of the basic pumping stage advance through each cycle of operation, the air or other fluid is sucked through intake port 18 from the suction pipe of the system into said chamber (see arrows) as the space between the trailing working face 35 of fast-moving piston 27'' separates from the leading working face 34 of slow-moving piston 28''. At the same time, fluid previously entrained in this manner between leading working face 34 of piston 27'' and trailing working face 35 of piston 28'' is being expelled through outlet port 19 and communicating duct 20 into working chamber 11 as these last-mentioned piston faces close on each other. It is during this cycle of pumping operation in working chamber 10 that compression of the fluid being evacuated therefrom into working chamber 11 ordinarily would cause retrograde leakage between the frictional faces of the pistons and casing walls back into the suction pipe. Due, however, to the addition of working chamber 11 and its pistons 27' and 28', the tendency toward slip will be neutralized to a great degree, because the fluid dis-

placed from working chamber 10 plus the fluid forced ahead of the same into communicating duct 20 will be sucked into the larger interior of working chamber 11, as indicated by the arrows. This is the primary stage of slip neutralization to which previous reference has been made. It also has been explained that neutralization of slip by this stage is not quite perfect, because there is an area between the frictional faces where rearward suction is opposed to forward pull of the pistons in working chamber 11 to such a degree that slight slip will occur. It is for this reason that the secondary slip-neutralization stage has been applied by the pumping action in working chamber 12. It will be seen that fluid evacuated by the pistons in working chamber 11 through outlet port 19' and communicating duct 21 into working chamber 12 will be accommodated, to include the contents of said duct, by the still further increased piston displacement in said chamber 12. In fact, such perfect neutralization of slip has been achieved as a result of the combined primary and secondary stages thereof that a vacuum pump constructed in accordance with the invention consistently produces a vacuum of 2 microns of mercury when operating at a shaft velocity of 800 R. P. M.

Having thus described the invention, I claim:

1. A multiple stage non-slip vacuum pump comprising: casing means providing a plurality of cylindrical working chambers which include a basic pumping chamber and a slip-neutralizing chamber of greater cubic capacity than said basic pumping chamber, each of said working chambers being closed by end walls and having intake and outlet ports disposed substantially 180 degrees apart, means providing a communicating duct leading from the outlet port of the basic pumping chamber to the intake port of the slip-neutralizing chamber, a pair of relatively movable segmental pistons rotatable in each working chamber on a concentric axis and being of length and diameter corresponding to those dimensions of the respective working chambers in which they are located, the angle between the leading and trailing faces of each piston being such that greater piston displacement will occur in the slip-neutralizing chamber than in the basic pumping chamber, and driving means to cause the pistons in each working chamber to move with variable velocities and to approach and recede from each other alternately in such manner that when the space between approaching faces is in communication with one port of the corresponding working chamber the space between receding faces is in communication with the other port, said driving means being constructed and arranged to cause the space between receding faces of the pistons in the slip-neutralizing chamber to be in communication with the intake port of said chamber while the approaching faces of the pistons in the basic pumping chamber are in communication with the outlet port of the latter chamber, whereby fluid will be sucked into the slip neutralization chamber simultaneously with expulsion of fluid from the basic pumping chamber.

2. A multiple stage non-slip vacuum pump as defined in claim 1, wherein the piston displacement in the slip-neutralizing chamber exceeds the piston displacement in the basic pumping chamber by an amount substantially equal to the interior fluid volume of the communicating duct.

3. In a multiple stage non-slip vacuum pump, the combination of a casing unit and a piston

unit removably mounted in said casing unit, said casing unit including a cylindrical body having a longitudinal bore of circular cross-section providing at least two aligned concentric working chambers of successively stepped up diameters having individual intake and outlet ports and a communicating duct leading from the outlet port of one chamber to the intake port of the other, and a closure plate for one end of the casing bore having shaft bearing means centrally disposed therein, said piston unit comprising a closure plate for the opposite end of the casing bore, means for removably attaching the last-mentioned closure plate to the casing body, said last mentioned closure plate having a central sleeve bearing therein, a driven sleeve journaled in the said sleeve bearing, a driven shaft having one end portion relatively permanently journaled in said driven sleeve and its opposite end removably journaled in the bearing means of the first-mentioned closure plate of the casing unit, a pair of coacting rotary pistons of appropriate size rotatable in each working chamber, one piston of each pair being affixed to the driven shaft for rotation therewith, a partitioning disc rotatably mounted on said driven shaft in interposed relation to the respective pairs of pistons and being adapted to rotatably bear against the peripheral wall of the casing bore in fluid sealing relation thereto, one of the pistons not affixed to the driven shaft being connected to the driven sleeve for rotation therewith, and means connecting both of the pistons not affixed to the driven shaft fixedly to the partitioning disc for rotation therewith.

4. In a multiple stage non-slip vacuum pump as defined in claim 3, the assembly-facilitation feature wherein the working chamber further from the casing end closed by the first-mentioned closure plate is the larger of the two and a shoulder is formed at the juncture of both working chambers, the partitioning disc being of a size and form to fit the larger diameter working chamber in abutting relation to said shoulder when the units are assembled.

5. A multiple stage non-slip vacuum pump comprising, in combination, casing means providing three concentric aligned working chambers of circular cross-section which include a basic pumping chamber and primary and secondary slip-neutralizing chambers, each of said working chambers having intake and outlet ports, means providing separate communicating ducts leading from the outlet port of the basic pumping chamber to the intake port of the primary slip-neutralizing chamber and from the outlet port of the last-mentioned chamber to the intake port of the secondary slip-neutralizing chamber, a pair of cooperative rotary pistons operatively mounted within each of said working chambers and adapted to suck fluid into the chamber through the intake port thereof and to discharge previously entrained fluid simultaneously through its outlet port, a driven sleeve journaled in said casing means in exteriorly projecting relation thereto and being fixedly connected to one piston in each working chamber, a driven shaft journaled in said driven sleeve in exteriorly projecting relation thereto and being fixedly connected to the pistons that are not fixedly connected to the sleeve, the respective pistons being arranged angularly on the driven sleeve and shaft in such manner that the pistons in two of the working chambers will be diametrically opposed to the pistons in the third working chamber when the pistons of each pair are in relatively closed dead-

center condition, external cylindrical bearing means provided on the casing means adjacent to the projecting portions of said driven sleeve and shaft in eccentric relation to the rotational axis thereof, and differential driving means for the pistons comprising a drum adapted to be connected operatively with a source of power for rotation in one direction and having apertured end walls, said drum having a concentric bearing in one of said end walls adapted to slidably and rotatably engage the eccentric bearing of the casing means, a crank affixed to the driven sleeve, a second crank affixed to the driven shaft, separate links pivotally connected at opposite ends to the respective cranks and to the said drum walls in such relation to the pistons when in dead-center condition that the cranks will be disposed in closely abutting relation diametrically opposite to the two pairs of pistons that are on the same side of the rotational axis with respect to each other, said cranks being weighted in relation to the pistons so as to counter-balance the same and being located on the same side of the driven shaft axis as the drum axis, the link connected to the crank which is leading the other in relation to the direction of drum rotation being connected to the drum at a point substantially diametrically opposite to the driven shaft axis and the link for the other crank being connected to the drum at a point close to the said driven shaft axis and substantially diametrically opposite to the drum connection of the first-mentioned crank, whereby the pistons in each working chamber are driven alternately at high and low speed.

35. 6. A multiple stage non-slip vacuum pump as defined in claim 5, wherein the differential driving means constitutes a removable unit wherein the means for affixing one crank to the driven sleeve is a longitudinally slidable key and the means for affixing the other crank to the driven shaft is a cross-pin engageable through the aperture in the outer end wall of the drum for detachment, whereby the complete unit may be withdrawn axially from the casing means.

45. 7. A multiple stage non-slip vacuum pump comprising: casing means providing a plurality of cylindrical working chambers including a basic pumping chamber and a slip-neutralizing chamber of greater cubic capacity than said basic pumping chamber, each of said chambers having intake and outlet ports; means providing a communicating duct leading from the outlet port of the basic pumping chamber to the intake port of the slip-neutralizing chamber; piston means 50 rotatable in each of said working chambers and comprising a pair of independently movable segmental pistons mounted for coacting rotation on an axis concentric to the working chamber in which located, each piston of each pair having leading and trailing faces lying substantially in planes intersecting on the rotational axis and which are separated by an included angle of less than 180 degrees whereby compression and expansion spaces are provided between adjacent 55 leading and trailing faces of both pistons; operating means adapted to drive both pistons of the pair in each working chamber alternately at high and low speed whereby as the leading face of a piston operating at high speed closes on the trailing face of the coacting piston compression of gas in the working chamber space between said faces will occur and conversely expansion will occur in the space between the trailing face of the high speed piston and the leading face of the low speed piston; and means adapted to coordi- 75

11

uate the motion of the pairs of pistons in the respective basic pumping chamber and slip-neutralizing chamber in such a manner that in the basic pumping chamber the space under expansion between receding piston faces will register with the intake port thereof simultaneously with registration of the compression space between closing piston faces with the outlet port, and in the slip-neutralizing chamber the space between piston faces under expansion will register with the intake port of said chamber simultaneously with registration of the space under compression with the outlet port.

8. A multiple stage non-slip vacuum pump as defined in claim 7, wherein the slip-neutralizing chamber and the face areas of the pistons therein are dimensioned to afford higher piston displacement than in the basic pumping chamber.

9. A multiple stage non-slip vacuum pump as defined in claim 7, wherein the slip neutralizing chamber and the face areas of the pistons therein

12

are dimensioned to afford higher piston displacement than in the basic pumping chamber by a volume substantially equal to that of the said communicating duct which extends between 5 chambers.

MICHAEL PEMMERL.
